UNITED STATES PATENT OFFICE

JOHN J. MACFAADDEN, OF CLEVELAND, OHIO, ASSIGNOR, BY MESNE ASSIGNMENTS, OF ONE-HALF TO REMINGTON RAND INC., OF NEW YORK, N. Y., A CORPORATION OF DELAWARE

VISIBLE INDEX

Application filed May 7, 1925. Serial No. 28,571.

This invention relates to visible indexes of the type having overlapping elements with their margins exposed and more particularly to an index adapted to follow the course of 5 orders for different products to different customers. One concrete embodiment of the invention is illustrated in the accompanying drawings, in which

Fig. 1 is a front view of the index;

10 Fig. 2 is a view in vertical section of one of the index elements on a larger scale; and

Fig. 3 is a front view of one of the index elements on a smaller scale.

The particular embodiment of the invention chosen for the purpose of illustration comprises the frame 1 having a series of index elements 2 mounted in the frame 1 in overlapping relationship. Each element comprises a back 3, a rail 4 hinged to the back 15 3 and having projecting ends 5 adapted to extend into channels at opposite edges of the frame 1. The rail 4 is flexible so that the ends 5 may be inserted into the frame by 20 bowing the rail 4. At the bottom of each index element is a transparent sheath 6 which has a portion 7 extending upwardly along the rear side of the back 3 and a portion 8 extending outwardly and upwardly in front of the back 3. The upper end of portion 8 is 25 turned inwardly at 9 to form a rounded or beaded finish. This sheath is preferably formed of transparent sheet celluloid and is 30 preferably secured to the back 3 by staples 10.

Signals 13, which may be formed of celluloid of different colors, are mounted on the sheath 6 as best shown in Figs. 2 and 3. These signals may be inserted, removed or 35 adjusted lengthwise of the sheaths at will.

Index sheets 11 are provided with recesses 40 12 to accommodate the staples 10 when inserted into the sheaths 6 as indicated in Figs. 2 and 3. These sheets may carry markings or designations of different kinds depending upon the use for which the device is intended 45 and the margins of the sheets are each provided with a row of markings so distributed that the markings form columns or rows transversely of the margins (vertical rows in the illustration) when the sheets are positioned in the series of sheaths. In Fig. 1

the markings comprise the vertical lines 15 dividing the margin into a plurality of sections, which in the present showing contain a series of numbers 16. In the illustration, index indicia comprising the name of a town 55 and theatre is also placed at the left-hand end of each horizontal row of sections.

In addition to the index sheets above referred to a designating index element is provided at one or both ends of the vertical rows 60 of markings above referred to. In Fig. 1 two such elements are shown, one at the top of the rows and one at the bottom. The element at the top of the vertical rows of markings comprises a card 17 pivoted to a rail 18 corresponding to rail 4 in Figs. 2 and 3. The lower margin of this card is divided 65 into a plurality of index sections containing names, which in the illustrated embodiment are motion picture titles. These index sections are arranged in alignment with the aforesaid vertical rows of sections extending transversely of the margins of the index elements 2 and associated with each name is a 70 number corresponding to the numbers with which it aligns. A corresponding index element 19 is provided at the bottom of the vertical rows of sections, the index sections on the element 19 corresponding to the index sections on the element 17. As illustrated 75 the element 19 is in the form of an insert in an index holder such as illustrated in Figs. 2 and 3.

A typical use of this invention is in keeping 80 records of bookings for photoplays in a distributing office. For such use the names of the theatres on the inserts 11 represent 85 customers of the distributing house and the names on the elements 17 and 19 represent the photoplays or other motion picture products available for distribution. The movable signals 13 give various indications 90 relative to the distribution of the available productions. For example, a green signal 95 over number 3 in the horizontal row to the right of "Melvern, Kans., Gem Theatre" may indicate that this theatre is being solicited to engage the motion picture entitled "News", and an orange signal over 4 in the 100 second horizontal row of markings may indi-

cate the Delphous Theatre in Mound City, Mo., has engaged the motion picture entitled "Westerns". By using signals of other colors or of different shapes further information may be conveyed at a glance. For more detailed information the overlying indexes may be swung upwardly to display any particular insert 11.

In addition to the index sheets 11 having the marginal rows of numbers and names of theatres further index sheets designated "run situation cards" may be employed. For example, where there are several theatres in the same city or town a run situation card common to these several theatres may be inserted in the holder 2 next preceding the holders containing sheets 11 for the respective theatres in the particular city. Thus in Fig. 1 a "run situation card" for St. Joseph, Mo., is shown next preceding the cards for the respective theatres in St. Joseph. The "run situation card" may, for example, show the possible number of runs, both minimum and maximum; also possible first, second and third runs. The best combination of pictures to sell may also be indicated on this card.

I claim:—

1. A visible index comprising a frame, a series of index elements mounted in the frame to swing into overlapping relationship with corresponding margins exposed, said margins being marked to form series of markings extending longitudinally and transversely of said margins, a name opposite each longitudinal series of markings, a designating index element mounted to swing over the uppermost of said elements and another such element under the lowermost of said elements, said designating elements having simultaneously visible names respectively aligned with said transverse series of markings.

2. A visible index or file comprising a panel, a series of holder cards, means detachably and hingedly connecting said holder cards to said panel for supporting said cards in overlapped spaced relation with their free margins projecting one beyond another, a transparent sheath on the free margin of each holder card, an index element hingedly connected to said panel adjacent said holder cards, the margin of same being divided transversely into a plurality of appropriately designated index sections, record cards movably carried by said holder cards, each having a marginal portion retained in the sheath of one of said holder cards in visible relation, said record cards having the marginal portion of each divided transversely into a plurality of sections aligned with said index sections on said index element, and index indicia on each of said record cards separate from said index sections.

3. A visible index or file comprising a panel, a series of holder cards, means detachably and hingedly connecting said holder cards to said panel for supporting said cards in overlapped spaced relation with their free margins projecting one beyond another, a transparent sheath on the free margin of each holder card, an index element hingedly connected to said panel adjacent said holder cards, the margin of same being divided transversely into a plurality of appropriately designated index sections, record cards removably carried by said holder cards, each having a marginal portion retained in the sheath of one of said holder cards in visible relation, said record cards having the marginal portion of each divided transversely into a plurality of sections aligned with said index sections on said index element, and index indicia on each of said record cards separate from said index sections.

4. A visible index or file comprising a panel, a series of holder cards, means detachably and hingedly connecting said holder cards to said panel for supporting said cards in overlapped spaced relation with their free margins projecting one beyond another, a transparent sheath on the free margin of each holder card, an index element hingedly connected to said panel adjacent said holder cards, the margin of same being divided transversely into a plurality of appropriately designated index sections, and record cards removably carried by said holder cards, each having a marginal portion retained in the sheath of one of said holder cards in visible relation, said record cards having the marginal portion of each divided transversely into a plurality of sections aligned with said index sections on said index element for indexing cooperation therewith.

Signed by me at Cleveland, Ohio, this 10th day of March, 1925.

JOHN J. MACFADDEN.
